DESIGN FOR A SWEAT SHIRT

Harry Charles, Norwich, N. Y., assignor to Norwich Knitting Company, Norwich, N. Y., a corporation of New York

Application June 1, 1938, Serial No. 77,487

Term of patent 7 years

To all whom it may concern:

Be it known that I, Harry Charles, a citizen of the United States and a resident of Norwich, in the county of Chenango and State of New York, have invented the new and original Design for a Sweat Shirt, of which the following is a specification, reference being had to the accompanying drawing, forming part thereof, in which—

The characteristic feature of the design resides in the specific decorative element on the front of the sweat shirt as shown.

I claim:

The ornamental design for a sweat shirt, as shown and described.

HARRY CHARLES.
